UNITED STATES PATENT OFFICE.

JOHN J. KANE, OF DOVER, NEW HAMPSHIRE, ASSIGNOR, BY MESNE ASSIGNMENTS, TO
UNITED SHOE MACHINERY COMPANY, OF PATERSON, NEW JERSEY, A CORPORATION
OF NEW JERSEY.

INSOLE-REINFORCING MACHINE.

1,236,715.

Specification of Letters Patent.

Patented Aug. 14, 1917.

Application filed October 24, 1907. Serial No. 398,912.

To all whom it may concern:

Be it known that I, JOHN J. KANE, a citizen of the United States, residing at Dover, in the county of Strafford, State of New Hampshire, have invented an Improvement in Insole-Reinforcing Machines, of which the following description, in connection with the accompanying drawings, is a specification, like letters on the drawings representing like parts.

This invention relates to machines for applying reinforcing material to insoles for boots and shoes.

Heretofore it has been customary to employ three or more operations in reinforcing insoles; first, a preliminary "forming-in" by which the reinforce is crudely shaped by hand to the insole; next, an applying operation commonly performed by a machine, such for example as that shown in U. S. Patent No. 614,860; and finally, a "following-up" operation by which the reinforced sole is completed. It is an object of this invention *inter alia* to avoid the necessity for so many operations, as by combining the second and third in one; and also to provide means for shaping and forming the reinforced sole expeditiously and accurately.

The invention may be described conveniently as embodied in a machine of the same type as that shown in the above mentioned patent.

In the drawings,—

Figure 1 is a side elevation of said machine, comparable to Fig. 2 of the patent aforesaid;

Fig. 2, a detail front elevation (viewed from the right in Fig. 1) of the parts of the machine which act upon the reinforce and insole;

Fig. 3, a transverse section of a reinforced insole illustrating a typical imperfection left by the operation of machines heretofore used;

Fig. 4, a transverse section of an insole, showing parts also disclosed in Figs. 1 and 2; and

Fig. 5, a transverse section of an insole, showing it applied to a last preparatory to the inseam stitching operation.

The insole may rest upon a work support 6, suitably movable to accommodate the feed of the work. A presser 8 may act upon the upper face of the insole in opposition to the

work support; and may be reciprocated conveniently to facilitate feeding the work by being mounted on a bell-crank 11 fulcrumed at 12 and rocked through its arm 13 by a cam 14. The latter is fixed upon a suitably supported shaft driven from a belt sheave 15. There may be also an anvil or former 16 and a bead forming tool 17, which may perform the double office of a forming tool and a four-motion feeding device to coöperate with the movable work support. To trim superfluous material from the edge of the reinforce the machine may have suitable trimming devices, such as the rotary disk cutters 19 and 20.

All of the devices referred to in the preceding paragraph may be exact counterparts of those disclosed in the patent aforesaid and may be operated in the same manner and by the same means. Obviously, therefore, reference may be had to said patent if the well-known construction and operation of said parts is not sufficiently understood.

In the illustrative machine embodying this invention the lip or bead of the insole stands between shaping and ironing tools 25 and 30. The tool 25 comprises a roller 26 appropriately mounted for rotation in a supporting shank bolted to the machine, by being journaled between two arms 27 and 28 (Fig. 4) the arm 27 lying between the roller and the lip or bead. It is thus seen that the shaping or ironing tool 25 is formed in two parts, one, the arm 27, which engages the side of the lip and another the roller 26 which acts in the angle between the lip and feather. The roller is arranged to press upon the reinforce overlying the insole feather, in order to iron them into secure adhesion. That side of the roller next to the bead is preferably beveled, together with the adjacent arm 27 of its supporting shank for purposes herein-after explained.

On the opposite or inner side of the bead is the shaping or ironing tool 30, which in the exemplary form comprises a frusto-conical roller, journaled on a vertical axis upon a shank bolted adjustably to the frame of the machine. The shaping and ironing tools 25 and 30 are relatively adjustable toward and from each other, as by providing the shank of the tool 30 with adjusting screws 31 and 32. This permits the tools to be moved horizontally toward or away

from one another to accommodate insole beads of different thicknesses.

As illustrated in Fig. 4 the adjacent faces of the shaping and ironing tools 25 and 30 for engaging and pressing against the opposite sides of the lip or bead are preferably substantially parallel and so inclined as to bend the insole bead inwardly toward the face of the sole.

10 In the operation of the above described specific machine the bead is placed between the ironing and forming tools 25 and 30, and the tools and sole relatively move to permit the former to act on the latter along 15 the length of the bead, as for example by having the sole fed past the tools in the manner and by the means described in said patent and shown in Fig. 1. Preferably the reinforce is to some extent laid over the bead 20 and onto the feather before being introduced to the action of the shaping and ironing tools 25 and 30 and this may be conveniently effected by the bead forming tool and the anvil or former hereinbefore referred to, 25 which may be constructed and may operate as described in said patent. When the reinforce and sole are acted upon by the shaping and ironing tools 25 and 30, said tools engage the insole lip, then covered with the 30 reinforce, and press the latter against the opposite sides of the lip. Preferably the tool 30 has at its lower end an acutely angular part arranged to enter completely into the extreme vertex of the angle formed 35 between the bead and the face of the sole. Thus, said tool crowds or tucks the reinforce completely into said angle. Also, said tool by entering said angle may serve to lift up the lip, if the latter be bent over, in order to 40 apply the reinforce properly to the inner face of the insole lip.

Fig. 3 shows in transverse section a reinforced sole presenting typical defects likely to remain after the sole has been reinforced 45 by the machine of said patent and similar machines which do not possess the advantageous features of construction contemplated by this invention. It will be noted in Fig. 3 that the insole lip is bent or 50 pressed and in consequence the reinforce, instead of being tucked properly into the inner angle of the lip, is for a considerable space entirely unattached either to the lip or the body of the insole. This is a serious 55 defect since when the needle which makes the inseam enters the unattached portion of the reinforce, it is likely seriously to tear it. Also, the needle and its stitch, by tending to draw the reinforce snugly into the lip 60 angle, may either tear the reinforce or overcome its adhesion to the sole and further detach it.

Devices embodying the present invention, however, cure the defects just referred to by 65 manipulating the lip so as to permit proper

access to the inner angle which it forms with the face of the sole and by properly applying the reinforce to the sides of said angle. A typical product of a machine embodying this invention is well illustrated 70 in Fig. 5, which in comparison with Fig. 3 clearly demonstrates its superior efficiency.

The forming and ironing tool 25 may also contribute to the above explained objects by assisting to iron the lip flat, instead 75 of permitting it to be bent as in Fig. 3. The beveled arm 27 supports the outer side of the lip and presses the lip against the circumferential face of the roller 30, while the angular edge of the roller 26 acts in 80 the angle formed by the intersection of the lip and feather, so as to tuck or press the reinforce into said angle, while at the same time pressing it against the lower portion of the side of the lip and the feather. With 85 this construction the lip is bent inward by reason of its engagement between the inclined faces of the tools 27 and 30, and the reinforcing material is tucked into the angle 90 of the lip and feather by the tool 26 which is mounted so as to be movable relatively to the lip bending tools in order to prevent a rupture of the reinforcing material where it may be loose in the angle, which fault is 95 found to occur if a fixed, drag tool is employed at this point.

The opposed action of the specific tools 25 and 30 may serve to press the reinforce snugly against opposite sides of the lip throughout its entire extent from the extreme base of the lip immediately adjacent the face and feather of the sole up to the crown of the lip. The adjustment already referred to by which the tools 25 and 30 may be moved relatively toward or away 105 from each other, permits the tools to be positioned properly for engaging lips or beads of any thickness.

The bending over or collapsing of the insole lip represented in Fig. 3, is of very 110 common occurrence, and nearly always the lip is bent inwardly. It is preferred, therefore, that the tool 30 or its equivalent have a species of plow-like action sufficient to lift or turn the lip upwardly and straighten 115 it. The specifically illustrated form of frusto-conical roller performs this office very effectively and at the same time may iron the lip out after it has been straightened.

When the above described operations take 120 place the cement or other adhesive by which the sole and reinforce are held together, is preferably in a green state,—that is to say, it is softened either by heat or moisture. The operation of the entire machine may act 125 upon green cement and the parts, while freely pliable, may be tucked and ironed to the best advantage. When the several operations heretofore employed have been necessary, the later operations, as for example, 130

the "following-up" operation hereinbefore referred to, have acted upon the reinforce and insole after the cement had dried. Obviously, this was a decided disadvantage. 5 For example, the sole shown in Fig. 3, being ready for the "following-up" operation and the cement being dried, the reinforce was securely cemented to the middle of the sole face and also securely cemented to the 10 feather. If, under these circumstances, a tool were pressed upon the reinforce in an attempt to tuck it into the angle of the lip, one of two disastrous results must necessarily follow: Either the reinforce would be torn, 15 or would be at some point or other detached from the sole. This is avoided by the operation contemplated by this invention, wherein the application of the reinforce is entirely completed when the adhesive is in condition 20 to permit free movement of the reinforce until finally shaped, whereupon the adhesive may be permitted to harden and dry.

Referring now to Fig. 4, the construction of the tools 25 and 30 shown for illustration, 25 is such that the bead is inclined inwardly toward the middle of the sole so as to present an acute inner angle. While this result is by no means indispensable, it has considerable advantage. When the sole shown 30 in Fig. 3 has been passed through a "following-up" machine, the latter will have so shaped the bead that it will stand substantially perpendicular to the face of the sole. Thereafter, when the sole is bent over a last 35 convex in cross section the bead will be turned outwardly, presenting an acute angle with the feather and an obtuse angle with the face of the sole. Thus when the upper and linings are lasted they must be crowded 40 into the acute feather angle of the bead or else in the process the bead will have to be manipulated so as to increase the angle. When, however, the result shown in Fig. 4 is produced, the subsequent fitting of the sole 45 to the last as shown in Fig. 5, presents on the feather side of the bead an obtuse angle to receive the margins of the lasted upper and linings; and an acute angle upon the inner side of the bead, such that the channel guide can obtain a firm hold on the work and properly maintain it in position to receive the stitches through the bead at its base.

Various advantages other than those particularly pointed out are provided by this invention, as will appear to those familiar with the art of reinforcing insoles. One of the most considerable advantages resides in the provision for completing the application 55 of the reinforce on a single machine, while the cement is green; and thereby avoiding successive operations some of which take place after the cement has dried more or less.

60 No attempt has been made to suggest or

describe the various forms in which this invention may be embodied, since as will appear to those skilled in the art a variety of different constructions and modes of operation may be employed in practising this invention without departing from the proper scope thereof. It is not essential that all the features of the invention be employed conjointly, since they are susceptible of separate use to advantage. 70

75 The definition of the scope of the invention is delegated exclusively to the subjoined claims.

What is claimed as new is:—

1. An insole reinforcing machine comprising, in combination, means preliminarily to lay the reinforce over both sides of the insole lip; subsequently acting means co-operating therewith to press and iron the reinforce against the faces of the lip from 80 base to crown; and provision for relatively moving the sole and said means, so that the latter shall act along the length of the insole lip.

2. An insole reinforcing machine comprising, in combination, means to lay the reinforce preliminarily over both sides of the insole lip; and bead finishing tools engaging 90 the lip from base to crown to complete the application of the reinforce. 95

3. An insole reinforcing machine comprising, in combination, means to lay the reinforce preliminarily over both sides of the insole lip; and bead finishing tools engaging 100 the lip from base to crown to shape the lip and complete the application thereto of the reinforce.

4. An insole reinforcing machine comprising, in combination, means preliminarily to introduce the reinforce to both sides of the 105 insole lip; bead finishing tools engaging the lip from base to crown; and mechanism for causing said means and tools to act simultaneously upon a bead, whereby the bead may be begun and completed on a single 110 machine.

5. An insole reinforcing machine comprising, in combination, means to introduce reinforce preliminarily to both sides of an insole lip and for feeding the insoles; and 115 opposed bead finishing tools held in fixed relation to each other both across and in the line of feed to complete the application of the reinforce.

6. An insole reinforcing machine comprising, in combination, means to introduce reinforce preliminarily to both sides of the insole lip; and opposed bead finishing tools continuously and progressively engaging the reinforced lip. 120

7. An insole reinforcing machine comprising, in combination, means to introduce reinforce to both sides of an insole lip; and means engaging the lip from base to crown for straightening the lip. 125 130

8. An insole reinforcing machine comprising, in combination, means for introducing reinforce preliminarily to both sides of the insole lip; and opposed tools continuously 5 engaging the lip to determine the position of the lip and apply reinforce thereto.
9. An insole reinforcing machine comprising, in combination, means preliminarily to introduce reinforce to opposite sides of 10 the insole lip; and lip positioning tools continuously and progressively engaging opposite sides of the lip.
10. An insole reinforcing machine comprising, in combination, means preliminarily 15 to introduce reinforce to both sides of the insole lip; and bead finishing tools continuously engaging the lip coöperating therewith to complete the application thereto of the reinforce.
11. An insole reinforcing machine comprising, in combination, means to apply reinforce to an insole lip, bead positioning means to bend the bead obliquely with relation to the sole face; and means for causing 25 the same to act along the length of the bead.
12. An insole reinforcing machine comprising, in combination, means to apply reinforce to an insole lip, bead positioning means to bend the bead inwardly toward the 30 middle of the sole; and means for causing the same to act along the length of the bead.
13. An insole reinforcing machine comprising, in combination, means to apply reinforce to an insole lip, combined bead positioning and bead ironing means to incline the bead obliquely with relation to the sole face; and means for causing the same to act 35 along the length of the bead.
14. A machine for reinforcing insoles having, in combination, a horizontal work support disk, a conical roll arranged to press the reinforcing material against the inner side of the lip of an insole supported on the work support and mounted to rotate about 40 a substantially vertical axis, and a pressure device mounted to rotate about a substantially horizontal axis coöperating with the conical roll to continuously press the reinforcing material against the lip.
15. A machine for reinforcing insoles, having, in combination, a horizontal work support, a conical roll arranged to press the reinforcing material against the inner side of the lip of an insole supported on the work 45 support and mounted to rotate about a substantially vertical axis, and a pressure device mounted to rotate about a substantially horizontal axis coöperating with the conical roll to press the reinforcing material against the lip, substantially as described.
16. A machine for reinforcing soles, having, in combination, a work support, means for bending and shaping reinforce material about the lip of an insole supported on the 50 work support, and compressing devices con- 45 tinuously and progressively engaging opposite sides of the reinforced lip, substantially as described.
17. A machine for reinforcing insoles, having, in combination, a work support, 70 means for bending and shaping reinforce material about the lip of an insole supported on a work support, and compressing devices continuously and progressively engaging opposite sides of the reinforced lip and arranged to bend the lip inward at an inclination to the surface of the sole, substantially 75 as described.
18. A machine for reinforcing insoles, having, in combination, a work support, 80 devices for progressively forming a bead or crimp in the reinforce material and securing it to the insole, an outside forming tool having an inwardly inclined lip engaging surface, an inside pressure roll having a periphery parallel to said surface, and means for continuously pressing the roll toward the forming tool, substantially as described.
19. A machine for reinforcing insoles, having, in combination, a horizontal work 85 supporting disk, a conical roll arranged to engage the inner side of the lip of an insole supported on the work support and mounted to rotate about a substantially vertical axis, and a fixed pressure device coöperating with 90 the conical roll to continuously press the reinforce material against the lip, substantially as described.
20. A machine for reinforcing insoles, having, in combination, a work support, 100 means for bending and shaping reinforce material about the lip of an insole supported on the work support, and compressing devices continuously and progressively engaging opposite sides of the reinforced lip from 105 base to top, substantially as described.
21. A machine for reinforcing insoles, having, in combination, a rotatable roll of substantially conical shape arranged to press the reinforcing material with its circumferential surface against the inner side of the lip, a pressure wheel having a surface constructed and arranged to press against the outer side of the lip and against the feather, and coöperating with said roll to continuously 110 press the reinforcing material against the lip and incline the lip obliquely inward with relation to the sole face, and means for supporting the insole with its lip between said roll and wheel.
22. A machine for reinforcing insoles, having, in combination, a rotatable roll of substantially conical shape arranged to press the reinforcing material with its circumferential surface against the inner side of the 115 lip, a pressure wheel having a surface constructed and arranged to press against the outer side of the lip and against the feather, and coöperating with said roll to continuously press the reinforcing material against 120
- 130

the lip and incline the lip obliquely inward with relation to the sole face, means for supporting the insole with its lip between said roll and wheel, and means for trimming the 5 reinforcing material.

23. A machine for reinforcing insoles, having, in combination, devices for progressively and continuously securing the reinforcing material to the insole lip or bead 10 comprising an outside forming tool having an inwardly inclined lip engaging surface, and an inside pressure roll having its circumferential surface substantially parallel to said surface, and means for supporting 15 the insole with its lip between said roll and the tool.

24. A machine for reinforcing insoles, having, in combination, a work support, a conical roll arranged to engage the inner 20 side of the lip of an insole supported on the work support and mounted to rotate about an axis substantially perpendicular to the face of the work support, and a pressure device coöperating with the conical 25 roll to press the reinforcing material against the lip.

25. A machine for reinforcing insoles, having, in combination, a rotary tapered roll at the inside of the lip having its larger 30 base engaging the face of the insole, and a pressure device at the outer side of the lip coöperating with said roll constructed and arranged to set the lip against the tapered circumferential surface of said roll thereby 35 to press the reinforcing material against the lip and bend the lip inwardly toward the middle of the insole.

26. A machine for reinforcing insoles, having, in combination, means to apply reinforcing material to the outside of the insole lip, and opposed means to bend the 40 lip obliquely with relation to the sole face and complete the application of the reinforce.

45 27. A machine for reinforcing insoles, having, in combination, a work support and a plurality of means for crimping the reinforcing material into a bead compressed from base to top, and bent inward at an inclination to the insole, said means operating 50 with the bead between them, one in advance of the other, substantially as described.

28. An insole reinforcing machine comprising, in combination, means to introduce

reinforce preliminarily to both sides of an 55 insole lip, and opposed bead finishing tools in fixed relation to each other to complete the application of the reinforce.

29. A machine for preparing reinforced insoles, having, in combination, means for 60 bending the lip of the sole inwardly and for pinching the same, and means for tucking the reinforcing material inwardly into the angle of the lip and feather.

30. A machine for preparing reinforced 65 insoles, having, in combination, lip shaping means for pressing against opposite sides of the lip of the insole to bend it inwardly, and additional means for tucking the reinforcing material into the angle of the lip and 70 feather.

31. A machine for preparing reinforced insoles, having, in combination, two tools for engaging the lip of the insole between them to bend the lip inwardly, and a third 75 tool movable relatively to said lip bending tools for tucking the reinforcing material into the angle of the lip and feather.

32. In a machine for preparing reinforced insoles, means for bending the lip of 80 the sole inwardly and for pinching the same to hold the reinforcing material securely to the lip, and means for tucking the reinforcing material inwardly into the angle of the lip and feather. 85

33. In a machine for preparing reinforced insoles, means for feeding the work and for pinching the lip of the insole to hold the reinforcing material securely thereto, and means for tucking the reinforcing 90 material into the angle of the lip and feather.

34. A machine for preparing reinforced insoles, having, in combination, two opposed tools for engaging and pressing a portion of 95 the lip of the insole between them, and a third tool movable relatively to said pressing tools for simultaneously tucking the reinforcing material on the same portion of the lip into the angle of the lip and 100 feather.

In testimony whereof, I have signed my name to this specification, in the presence of two subscribing witnesses.

JOHN J. KANE.
